DESIGN FOR A GAME DEVICE

Warren Henry Mercer, Anaheim, Calif.

Application November 19, 1943, Serial No. 111,730

Term of patent 7 years

To all whom it may concern:

Be it known that I, Warren Henry Mercer, a citizen of the United States, residing at Anaheim, in the county of Orange and State of California, have invented a new, original, and ornamental Design for a Game Device, of which the following is a specification, reference being had to the accompanying drawing, forming part thereof.

I claim:

The ornamental design for a game device, as shown.

WARREN HENRY MERCER.
